PULP SCREEN

Stephen A. Staeger, Hamilton, Ohio, assignor to
 The Black-Clawson Company, Hamilton, Ohio,
 a corporation of Ohio

Application July 8, 1940, Serial No. 344,332

16 Claims. (Cl. 92—34)

This invention relates to screening apparatus and to the removal of rejected material therefrom.

One object of the invention is the provision of a screening apparatus for paper pulp, adapted to effectively mix the pulp being screened with an added stream of water or pulp.

Another object is the provision of screening apparatus having means for automatically controlling the disposal or withdrawal of the tailings or rejects in accordance with the amount of tailings or rejects present.

Another object of the invention is the provision, in a screening machine, of an automatic valve and control means therefor controlling the rate of removal of rejected material from the screening chamber and arranged to automatically increase the rate of reject removal when the pressure on the supply side of the screen increases.

Another object of the invention is the provision, in a screening machine for paper pulp, of a conduit communicating with a reject collecting space on one side of the screening surface of the machine, and a rotary reversible valve which controls the flow of the rejected material through the conduit.

Other objects and advantages of the invention will be apparent from the following description, the appended claims, and the accompanying drawing.

In the drawing.

Fig. 1 is a top plan view of a screening apparatus embodying the present invention;

Fig. 2 is a side elevation of the same, with a portion of the screen and the reject valve shown in section; and

Fig. 3 is a diagrammatic showing of the electrical connections of the valve operating motor.

Referring more particularly to the drawing by reference numerals, like parts being designated by the same numerals in the several views, the invention, in its preferred form has been shown embodied in a screening apparatus for screening material such as paper pulp. The screening apparatus, as shown, comprises a container including a casing wall 10 having a top cover plate 11 removably positioned thereon. The pulp supplied to the screen comes in through the supply pipe 12 and enters the inlet chamber 13 and must travel through the perforated cylindrical screen surface 14 before moving through the discharge passage 15.

Passage of the pulp through the screening surface 14 is greatly facilitated by a large number

of scraping blades 16 having a construction as more fully disclosed in my prior application Serial No. 285,362, filed July 19, 1939, which has now issued as Patent No. 2,347,716. These blades extend along the inner surface of the screen and are carried yieldingly by springs 17 mounted on carrying rings 18 of a rotatable spider 19 which is connected to a shaft 20 operated from a motor 21 through suitable gearing in the gear box 22. When a large number of such blades are used rapidly succeeding passes of the blades over each hole will be secured, without the necessity of such high operating speeds as will set up considerable and disturbing centrifugal forces or undue agitation of the body of stock inside the screen. By avoiding such undue agitation and preventing unduly high centrifugal forces, the main body of stock within the screen is maintained comparatively quiescent, even when large volumes of stock are being passed through the screen, and consequently heavy impurities can settle by gravity to the bottom of the screen and not be thrown outwardly by the centrifugal force to pass through the holes of the screen along with the screened stock. And by using a sufficiently large number of blades, passing over the holes at a comparatively low rate of travel, the blades nevertheless will operate along the supply side of the screen to give such rapid succession of gentle cleaning actions that the stock will be prevented from matting to plug up or clog the holes and also from matting or collecting in advance of the blades to give a maintained accumulation which will produce an objectionable matting of the fibers. In operation the satisfactory results of this invention are attained when the blades are operated at such low angular velocity as to produce centrifugal forces which are negligible with respect to the discharge of heavy impurities through the screen and yet are moved across the screen and the holes thereof and through the body of stock adjacent the screen at such rate that the rapid succession of movements gives gentle cleaning actions whereby the fibers are prevented from accumulating and matting over the holes to plug or clog them up and are prevented from maintained accumulation in front of the respective blades to give an undesirable matting over of the fibers.

The pulp or pulped stock being screened in this machine will contain in suspension fibrous material sufficiently fine to pass through the openings of the screen, and also usable fibrous material or pulp which has not been sufficiently

separated so that it is fine enough to pass through such openings and this larger or less disintegrated fibrous material or pulp which is of such size that it will not pass through the openings of the screen is rejected by the screen and tends to remain in suspension in the space on the inlet or supply side of the screen. In addition, the stock or pulp being screened as it passes to the paper making machine still contains, at times, some non-fibrous or unusable heavy materials such as particles of metal, sand, and the like which should be removed and finally rejected from the system so that they will not contaminate the screened pulp or stock which is passed to the paper making machine. Herein the term rejects is used broadly to cover material which does not pass through the screen and, as is clear, the larger masses of fibrous material which require further treatment are separated or segregated so as to avoid objectionable variations in consistency which would affect the operation of the screen, and so that they may be returned for further treatment or refining to make them available to be returned to the screen and for use on the paper machine; whereas the sand and grit and other dirt which is also removed is collected or segregated separately and is discharged or finally rejected from the system. The rate of flow through the screen is dependent upon the pressure of the pulp supplied to the inlet pipe 12, as the blades keep the screen openings from clogging.

At one side of the screening surface, opposite to the outlet passage 15, is an auxiliary supply passage 23 in free communication with the space surrounding the screening surface, and water or additional pulp that has previously been screened may be supplied through this passage 22 under suitable pressure to the discharge side of the screening apparatus. The material added through the auxiliary inlet 23 thoroughly mixes with the screened pulp issuing through the perforations in the screening surface as the added material flows around opposite sides of the screening surface. The screened pulp passing through the discharge passage 15 will thus be of a substantially uniform consistency, with the fibers in a thoroughly dispersed condition and free of any massing or collection of fiber groups.

Any lighter impurities, foam, etc., that may tend to collect at the top of the screen, at its inlet side, flow up through the upwardly extending pipe 24 which extends high enough so that these impurities may be retained at a suitable level which permits the withdrawal of gas or air, through the discharge opening at or near the top of pipe 24. The heavy impurities that settle down, due to gravity effect, in the lower portion of the inlet chamber 13 may be periodically withdrawn through a conduit 25 which extends downwardly from the lower wall 26 of the screening chamber.

The screening apparatus is so arranged as to provide an effective control of the rate at which reject material is removed from the supply side of the screen. The rejects, that include heavy matter that settles rapidly to the bottom of the screening chamber and the larger pieces of fibrous material that will not pass through the perforations in the screening surface, accumulate in the space just above the lower wall 26 of the screening machine and are slowly swept around until they enter the top of conduit 25. This conduit has a downwardly projecting extension 29 in which there are two shut-off valves 30

and 31, suitably spaced apart so that any sand, and bits of metal or other matter substantially heavier than water, together with the heavier or larger fibrous pieces may be trapped or segregated between the two valves, and occasionally discharged by opening the lower valve 31 when the upper valve 30 is closed, and then closing the lower valve 31 and opening the upper valve 30 to collect additional heavy material which should be wasted. These valves 30 and 31 may be manually controlled by the operator, as occasion may require, dependent upon the proportion of foreign matter in the pulp being treated.

Extending laterally from the pipe extension 29 is a branch passage 33 through which reject material is periodically and automatically discharged at a controlled rate. This branch passage 33, which is preferably provided with a normally open shut-off valve 34, extends to an automatically operable rotary valve 35 having a passage 36 which is adapted to alternately place the end of the passage 33 in communication with a reservoir chamber or standpipe 37 as shown in full lines in Fig. 2 and then place the standpipe 37 in communication with a discharge pipe 40 as indicated in dotted lines. A manually operable valve 38 arranged between valve 35 and the lower end of the standpipe 37 may be opened to any desired extent to provide desired throttling action and give some suitable rate of flow of material into the pipe 37. The upper end of the pipe 37 is closed against the flow of fluid therethrough by a plate 39, and the pipe is of considerable height so as to form a collecting and reservoir chamber 35 in which the reject material flowing from the passage 33 may be trapped under such pressure as exists on the supply side of the screening surface. If the pressure on the supply side of the screening surface is increased, it will be apparent that more reject material will flow up into the standpipe 37 when the passage 36 is in the position shown in Fig. 2 of the drawing. If the pressure existing on the supply side of the screening surface is less than some normal value, then 45 a correspondingly smaller amount of material will flow up into the standpipe when placed in communication with the passage 33. The pressure on the supply side of the screening surface increases when the proportion of reject material 50 present increases, this increase in pressure being due to the increase in the consistency of the stock on the supply side of the screening surface and the reduced rate of flow of material through the screen on account of this increase in consistency, 55 as the supply of stock to the screen is maintained. The rate of movement of the rejected material into the standpipe 37, when communication is established to that pipe, will thus accord automatically with the requirements for reject removal.

After placing the branch passage 33 in communication with the bottom of the standpipe 37, the valve 35 is turned so as to interrupt communication between these parts and establish communication from the lower end of the standpipe to the discharge pipe 40. The material rejected through the pipe 40 is composed largely of usable fibrous pieces too large to pass through the screen perforations, together with a quantity of smaller fibers and with only a comparatively small proportion of heavy extraneous matter, since the heavy particles settle down through the extension pipe 29 and are discharged through the lower end of that pipe. The fibrous materials withdrawn through the pipe 40 may therefore be

treated to a further refining action and the good fibers saved.

The valve 35 is periodically operated by means of an electric motor 43, carried on the base 44 which serves as a support for the motor 21 and as a support for the frame 44 on which the screen itself is carried. The motor 43 has a speed reducing gear box 45 which is provided with a rotatable shaft 46 connected to the valve 35. Motor 43 is a reversible motor, as indicated in Fig. 3, having a reversing mechanism switch 47 which changes the phase relation of two phases of the three-phase supply by selectively energizing the relay coils 47a and 47b. These coils control the sets of switches 47' and 47" respectively so that one set is closed and the other opened. The motor driven shaft 46 is provided with limiting mechanism such as a cam 48 of any suitable character by means of which the switch 47 is reversed automatically after a predetermined part of a revolution of the shaft 46. The construction is such that the shaft 46 turns through a predetermined part of a revolution and then automatically reverses its direction of rotation, the speed of operation of the shaft being such as to place the branch passage 33 in communication with the standpipe 37 several times per minute. Since the valve member 35 operates first in one direction and then in the other, the fibers of the pulp that might tend to find their way between the valve and the housing in which the valve turns will be promptly freed, and the fibers will not collect or accumulate in this operating clearance space around the movable valve member. If the valve 35 were continuously driven in only one direction, paper pulp fibers would gradually accumulate between the movable valve member and its enclosing wall to such an extent as to place an extremely large drag on the movements of the valve member and finally produce such a packing of the fibers as to jam the valve and make continued movement impossible. This objection however is avoided in accordance with the present construction.

The reversible electric motor 43 remains energized continuously during normal operation if the pulp supplied to the screening apparatus contains a comparatively large proportion of material that should be rejected. There is an automatic means however for temporarily deenergizing the motor if the pressure on the supply side of the screening surface decreases below some predetermined value. This decrease in pressure takes place when there is only a comparatively small proportion of material to be rejected from the screen, and under such conditions the motor 43 is automatically deenergized by means of an electric switch including a pair of contact points 52 and an electrical conductor 53 which is carried by a flexible diaphragm 54 arranged in a housing 55 and adjustably tensioned to a suitable normal position by spring 50. The space at one side of the diaphragm 54 communicates, through a pipe 56, with the supply side of the screen, the pipe 56 connecting, as shown, to the conduit 25. When the pressure on the supply side of the screen is slightly below some normal value the contact member 53 will be moved away from the contact points 52 and the circuit to the motor will be broken, since both switch controlling relay coils 47 will be deenergized. The withdrawal of the rejected material through the branch passage 33 will therefore cease until sufficient material to be rejected collects in the screen and causes an increase in pressure, whereupon the contact 53 will be moved to contact closing position auto-

matically and the motor started again. The rate of withdrawal of the rejects from the screening machine is thus automatically controlled in accordance with the amount of tailings or rejects present in the material being treated. It will be apparent that only a comparatively small proportion of fine usable fibers will be withdrawn as the rejected material is removed, and the amount of material flowing out through the discharge pipe 40, and either wasted or returned for further pulping, will be kept at a low value and so controlled as to its rate of withdrawal as to be in accordance with the actual requirements under different conditions of use.

A time switch is preferably provided for use in limiting the operation of the reject valve when the screen is used on very clean stock. In such case, where the amount of rejects is exceedingly small, the time switch may be set so that the motor will only operate a part of a minute out of every fifteen minute or other suitable period. Since there is no direct through path from the screen through which the rejects can pass, the time switch can interrupt the operation of the valve and it is immaterial where the valve stops, since the stock and water from the screen cannot be discharged directly to the outside. The time switch as well as the pressure switch can therefore be used together to interrupt the valve operation and thus save pulp when the amount of rejects present is exceedingly small. With the time switch, the screen can handle stock at very low pressure or without constantly adjusting the pressure switch for different pressures. This time switch, as shown, includes contacts 58 connected in series with the contacts 52 and adapted to be closed by the contact plate 59 which is operated periodically by projections 60 on a rotatable plate 61. This plate 61 is rotated slowly by a suitable time clock or constant speed motor 62. The starting and stopping of the motor 62 is of course under the control of the operator.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. In a screening machine for paper pulp, in combination, a container having a screening surface and a reject collecting space on one side of the screening surface, a reject discharge passage connected to said reject collecting space, means for receiving a limited quantity of the rejected material, a valve in said passage operable to one position to establish communication between said passage and said receiving means providing for the flow of rejected material thereto, and valve drive means operable to periodically shift said valve to another position in which said passage is closed and said limited quantity of rejected material is discharged from said receiving means.
2. In a screening machine for paper pulp, in combination, a container having a screening surface and a reject collecting space on one side of the screening surface, a conduit extending downwardly from the reject collecting space, control means adjacent the lower end of the conduit operable to periodically pass limited quantities of heavy rejected material downwardly through the conduit, a branch passage projecting from said conduit ahead of said control

means, a rotary valve for closing and opening said passage, means for receiving a predetermined limited quantity of said rejected material under control of said valve, and automatic valve drive means operable to periodically reverse the direction of rotation of the valve after a predetermined annular movement thereof in one direction to provide for discharge of said rejected material from said receiving means.

3. In a screening machine for paper pulp, in combination, a container having a screening surface and a reject collecting space on one side of the screening surface, a conduit extending downwardly from the reject collecting space, control means adjacent the lower end of the conduit operable to periodically pass limited quantities of heavy rejected material downwardly through the conduit, a branch passage projecting from said conduit ahead of said control means, a valve in said branch passage, automatic means for periodically operating said valve to discharge rejected material from said passage, and means associated with said valve to limit flow therethrough to a measured quantity each time the valve opens.

4. In a screening machine for paper pulp, in combination, a container having a screening surface and a reject collecting space on the supply side of the screening surface, a reject discharge passage connected to said space, a valve in said passage operable to control flow of rejected material therethrough, a standpipe communicating with said valve to receive material from said passage, said valve having means for placing the conduit in communication with said standpipe and having additional means for thereafter segregating the standpipe from the passage and opening the standpipe to discharge.

5. In a screening machine for paper pulp, in combination, a closed container for receiving paper pulp under pressure and having a screening surface and a reject collecting space on the supply side of the screening surface, a reject discharge passage connected to said reject collecting space, a reservoir chamber connected to said passage and extending upwardly and having an upper end closed against free flow of fluid therethrough, and valve means operable to one position to establish communication between a low portion of the reservoir chamber and said passage providing for flow of a quantity of rejected material into said chamber dependent upon the pressure in said reject collecting space, said valve means being operable to another position to segregate said reservoir chamber from the passage and to open said reservoir chamber to discharge.

6. In a screening machine for paper pulp, in combination, a closed container for receiving paper pulp under pressure and having a screening surface and a reject collecting space on the supply side of the screening surface, a reject discharge passage connected to said reject collecting space, a compression chamber connected to said passage for receiving and segregating a limited quantity of the rejects from said conduit under the pressure prevailing at the screen intake, and means for periodically placing said compression chamber alternately into communication with said passage and with a discharge opening.

7. In a screening machine of the character described, in combination, a closed container adapted to receive material to be screened under pressure, said container having a screening sur-

face and a reject collecting space on the supply side of the screening surface, a reject discharge passage connected to said reject collecting space, an automatically operable valve for controlling flow through said passage for periodically discharging rejects from said conduit, means associated with said valve to limit the flow therethrough to a measured quantity each time the valve opens, drive means operating said valve

10 to close and open the passage for the passage of rejected material therethrough, and means responsive to the pressure of the material on the supply side of the screening surface for controlling the operation of said drive means.

15 8. In a screening machine, in combination, a container having a screening surface and a reject collecting space on one side of said screening surface, a compression chamber connected to said reject collecting space for segregating a

20 quantity of rejects from said space under the pressure prevailing within the container, valve means for periodically placing said compression chamber alternately into communication with said space and with a discharge opening, and pressure responsive means operable in accordance with the pressure on the inlet side of said screening surface for controlling the operation of said valve.

25 9. In a screening machine, in combination, a container having a screening surface and a reject collecting space on one side of said screening surface, a compression chamber connected to said reject collecting space for segregating a limited quantity of rejects from said space under

30 the pressure prevailing at the screen inlet, valve means for periodically placing said compression chamber alternately into communication with said space and with a discharge opening, and time controlled means for automatically controlling the operation of said valve.

35 10. In a screening machine for paper pulp, in combination, a closed container adapted to receive paper pulp under pressure, said container having a screening surface and a reject collecting space at the bottom of the container on the supply side of the screening surface, a conduit extending downwardly from said space, means adjacent the lower end of said conduit for segregating and discharging measured quantities of

40 finally rejected material, a branch passage extending laterally from said conduit ahead of said last-mentioned means, an oscillatory valve in said passage, a standpipe projecting upwardly from said valve for receiving a quantity of rejected material from said conduit dependent upon the pressure on the supply side of the screening surface, said branch passage having a discharge opening, said valve being operable to successively place said standpipe in communication with said passage and with said discharge opening, a reversible motor for operating said valve in reverse directions and providing continued valve movements while the motor is energized, and pressure responsive means sub-

45 ject to the pressure on the supply side of the screen for automatically deenergizing the motor when the pressure on the supply side of the screen is below a predetermined limit.

50 11. A screening machine for paper pulp stock to be supplied to a paper making machine comprising a screen casing, an annular screening surface within said casing, means for supplying pulp to the inside of the screening surface, the space between the screening surface and the casing defining an annular discharge chamber for

pulp flowing through the screen, said casing having an outlet opening at one side of the screening surface and having an auxiliary supply passage for the supply of screened pulp and water leading into the discharge chamber at the other side of the screening surface so that the annular screening surface is between the auxiliary supply passage and said outlet opening with resultant mixing of the auxiliary supply with the pulp flowing through said screen.

12. A screening machine for paper pulp comprising a screen casing, an annular screening surface within said casing, means for supplying pulp to the inside of the screening surface, the space between the screening surface and the casing defining an annular discharge chamber for pulp flowing through the screen, said casing having an outlet opening at one side of the screening surface and having an auxiliary supply passage for the supply of screened pulp and water leading into the discharge chamber at the other side of the screening surface with resultant mixing of the auxiliary supply with the pulp flowing through said screen, a reject removal passage connected to the space on the supply side of the screening surface, and means within said passage for periodically discharging rejected material through said pipe.

13. In a screening machine of the character described, in combination, a closed container adapted to receive material to be screened under pressure, said container having a stationary screening surface and a reject collecting space connected to the supply side of the screening surface, valve means for controlling said reject collecting space and for periodically discharging rejects from said collecting space, drive means operating said valve means to open and close the same to control the flow of rejects therethrough to and from said reject collecting space, and means automatically operable when the pressure of the material on the supply side of the screen exceeds a predetermined value for starting said drive means.

14. In a screening machine of the character described, in combination, a closed container adapted to receive material to be screened under pressure, said container having a stationary screening surface, means for supplying material to be screened to one side of said screening surface, means for discharging fibrous material passing freely through said screen, a discharge passage connected to the space on the supply side of said screen for receiving dirt and pulp material of size too great to pass through said

screen, means for segregating and finally discharging from the system said dirt, and means connected to said discharge passage and responsive to an increase in the pressure conditions on the supply side of said screen for cyclically discharging the rejected fibrous material, said latter means being operable to vary the timing of said discharge cycles to maintain the pressure on the supply side of said screen within predetermined limits.

15. In a screening machine of the character described, in combination, a closed container adapted to receive material to be screened, a screen within said container, means for segregating and withdrawing fibrous material of size too large to pass through said screen, and means for controlling the discharge of said segregated material comprising a reversible valve, means for receiving a predetermined limited quantity of said segregated material under control of said valve, and means for reversing the operation of said valve so that the reverse movement of the valve will discharge said segregated material from said receiving means and overcome any tendency of fibrous material to accumulate under pressure between the surface of the valve and the valve casing, whereby to prevent such accumulation as will materially interfere with or stall the operating of said valve.
16. In a screening machine for paper pulp, in combination, a screen chamber having a screening surface adapted to operate under pressure and a reject collecting space on one side of the screening surface, a reject discharge passage connected to said reject collecting space, a closed receiving chamber for receiving a limited quantity of the rejected material, valve means in said reject discharge passage operable to one position for establishing a flow between said reject collecting space and said receiving chamber of said limited quantity of reject material under the pressure differential existing between said screen chamber and said receiving chamber, said flow through said valve terminating when the pressure conditions within said respective chambers have been substantially equalized, said valve means being operable to another position for closing said reject discharge passage and opening said receiving chamber for the discharge of said material therefrom, and means for operating said valve means after the flow therethrough has substantially ceased to avoid the plugging of the valve by the deposit of pulp fibers thereon.
